MANUAL DATA ENTRY KEYBOARD CONSOLE

Edward J. Sabella, Vestal, and Rae F. Tankard, Owego,
N.Y., assignors to International Business Machines Cor-
poration, New York, N.Y., a corporation of New York

Filed July 16, 1964, Ser. No. 80,895

Term of patent 14 years

(Cl. D26—5)

FIG. 1

FIG. 2

FIG. 3

FIG. 4

FIG. 5

FIG. 6

FIG. 1 is a front perspective view of a manual data entry keyboard console showing our new design.

FIG. 2 is a top plan view of the same.

FIG. 3 is a front elevational view of the same.

FIG. 4 is a rear elevational view of the same.

FIG. 5 is a right side elevational view of the same.

FIG. 6 is a left side elevational view of the same.

The dominant features of our design reside in those portions shown in full lines on the drawing.

We claim:

The ornamental design for a manual data entry keyboard console, as shown and described.
